(Continued)

Primary Examiner — Cynthia Ramirez*(74) Attorney, Agent, or Firm* — Zhigang Ma(57) **CLAIM**

The ornamental design for a trash can, as shown and described.

DESCRIPTION

FIG. 1 is a front, right, and top perspective view of a trash can, showing my new design;

FIG. 2 is a rear, left, and bottom perspective view thereof;

FIG. 3 is a front elevational view thereof;

FIG. 4 is a rear elevational view thereof;

FIG. 5 is a left side elevation view thereof;

FIG. 6 is a right side elevation view thereof;

FIG. 7 is a top plan view thereof;

FIG. 8 is a bottom plan view thereof.

FIG. 9 is an enlarged view of an encircled area labeled "9" in FIG. 1; and,

FIG. 10 is a perspective view when the lid is opened.

The broken lines depict portions of the trash can that form no part of the claimed design.

The dot-dash broken lines in FIGS. 1 and 9 framing portions of the claimed design that are illustrated for enlargements form no part of the claimed design.

1 Claim, 10 Drawing Sheets(56)
